UNITED STATES PATENT OFFICE.

BRYSON D. HORTON, OF DETROIT, MICHIGAN.

ELECTRICAL SWITCH.

1,127,442.

Specification of Letters Patent.

Patented Feb. 9, 1915.

Application filed November 25, 1913. Serial No. 802,878.

To all whom it may concern:

Be it known that I, BRYSON D. HORTON, a citizen of the United States, residing at Detroit, in the county of Wayne and State 5 of Michigan, have invented certain new and useful Improvements in Electrical Switches, of which the following, taken in connection with the accompanying sheet of drawings, is a full, clear, and concise description.

10 This invention relates to certain details of improvements in electrical switches of the armor or iron clad type, that is a switch which is protected by a metallic housing consisting of receptacle and cover portions. 15 In this specific type of switch, the stationary and movable contacts are mounted upon a base of insulating material attached to the bottom of the receptacle. The movable contacts are pivotally mounted to the base 20 and are operated by a crank or operating member provided with a bearing in the side of the case and extending outside to provide for exterior manipulation.

25 My present improvement consists in providing means for positively holding the switch contacts in their "on" position when they are manipulated to make electrical connection and to accelerate the breaking of the connection between the contacts upon 30 the manipulation of the operating crank or handle to effect this result.

35 In the accompanying sheet of drawings: Figure 1 illustrates a top plan view of a switch incorporating my invention the cover of the receptacle being open and the contacts shown in their "on" position, Fig. 2 is a side view in elevation showing the parts in like position, and Fig. 3 is a cross sectional view taken on line a—a of Fig. 1 with the 40 contacts shown in their "off" position.

In detail 1 indicates a metallic receptacle provided with a hinged cover 2.

3 indicates a block of insulating material fast to the bottom of the casing 1. On this 45 block of insulating material stationary jaw contacts 4 and pivoted knife blade contacts 5 are mounted. The knife blade contacts 5 are connected by means of a cross-head 6 of insulating material. The cross-head 6 is 50 provided with an eye or retaining member 7 which has operable connection with one end of the crank or operating handle 8, the opposite end being provided with a knob 9. The crank 8 is provided with an intermediate 55 U-shape portion 10 having a bearing in the side of the casing 1, the bearing having

such relation to the pivotal points of the knife blade contacts 5 as to provide for a full effective throw of the knife blade contacts when the operating handle is manipulated to make or break the connection between them. 60

In order to accelerate the breaking of the connection when the operating crank is manipulated, so that a quick or snappy break 65 will occur, I employ a spiral spring 11 one end of which is connected to the operating crank by an eye 12 the other end being connected by an eye 13 to one end of the casing. This spring, as will be observed, is expanded 70 when the movable contacts are thrown into their "on" position, the stored up energy of the expanded spring spending itself to accelerate the return movement of the movable contacts to their "off" position when 75 the crank is operated in the reverse direction to break the connection between the contacts. In order to hold the knife blade contacts in their "on" position and to overcome the power of the spring 11 the tendency of which is to normally establish open 80 electrical connection between the contacts, I mount upon the side of the casing at 14 a steel sheet metal spring 15 bent at 16 in the manner shown. This spring member is 85 so positioned that it will lie in the path of a portion of the operating crank and be engaged thereby when the latter is manipulated to throw the knife blade contacts into their "on" position. The bent end 17 of 90 this spring member will engage the operating crank and be deflected thereby forcing it outwardly and permitting the crank to pass or fall within the curved or bent portion 16 thereof where it is retained by the 95 spring tension thereof. When the operating crank is manipulated to break the electrical connection between the contacts the holding ability or spring tension of this member 15 is overcome thus permitting the 100 passage of the operating crank on its outward oscillation. The full tension of the spring 11 is exerted to quicken or accelerate this movement so that a quick break between the switch contacts is effected. The spiral 105 spring 11 and spring member 15 both tend to prevent a partial connection being established between the contacts and insure a full positive connection being established between them. Furthermore, spring 11 prevents the accidental closing of the circuits 110 as a considerable force is required to over-

come its tension during the manipulation of the switch.

Having thus described my invention what I claim as new herein and desire to secure 5 by Letters Patent is:

1. In an iron clad switch of the character described in combination with stationary and movable contacts, a substantially U-shaped operating member co-operatively 10 associated with the movable contacts and extending through the side of the casing, an expansion spring connected at one end to one side of the casing and its other end to the U-shaped operating member, said ex- 15 pansion spring having a tendency normally to accelerate the movement of the U-shaped operating member when it is manipulated to break the electrical connection between the contacts and means for overcoming the 20 tension of said expansion spring, said means adapted to engage the U-shaped operating member when manipulated to throw the contacts into contact making position.

2. In an iron clad switch of the character

described in combination with stationary and movable contacts, a substantial U-shaped operating member associated with the movable contacts and mounted in the side of the casing and adapted to move the movable contacts through a substantial arc, 30 an expansion spring connected to said operating member and to the casing, said spring normally tending to exert its spring power to accelerate the movement of the movable contacts when being thrown to their "off" 35 position, and a leaf spring mounted upon the side of the casing in position to engage the operating member and hold the same against the tension of said expansion spring when the movable contacts are thrown into 40 circuit-established position.

In witness whereof I have hereunto set my hand in the presence of two subscribing witnesses this 21st day of November, 1918.

BRYSON D. HORTON.
